ATOMIZER OR SPRAYER

Rome C. Seyforth, Shelby, Ohio, assignor to
Shelby Metal Products Company, Shelby, Ohio

Application March 21, 1938, Serial No. 197,111

4 Claims. (Cl. 299—88)

This invention relates to improvements in atomizer or sprayer.

The main objects of this invention are:

First, to provide an atomizer or sprayer which is well adapted for embodiment in small sprayers such as perfume sprayers or sprayers adapted for spraying fluids such as are used for cleaning windshields and the like.

Second, to provide a sprayer or atomizer which is adapted for use for actuation with one hand and when held in any position—that is, upright, upside down or sidewise as may be convenient.

Third, to provide a sprayer having these advantages which does not leak when in any position of non-use.

Fourth, to provide a sprayer having these advantages which may be very economically produced and at the same time is very strong and durable.

Objects relating to details and economies of the invention will appear from the description to follow. The invention is defined and pointed out in the claims.

A preferred embodiment of the invention is illustrated in the accompanying drawing, in which:

Fig. 1 is a side elevation of a sprayer embodying the features of my invention of such dimensions that it may be used as a perfume sprayer, atomizer, or the like.

Fig. 2 is a view illustrating one of the small sprayers grasped by a hand and in actuated position.

Fig. 3 is an enlarged longitudinal section on line 3—3 of Figs. 4 and 5.

Fig. 4 is a transverse section on the broken line 4—4 of Fig. 3.

Fig. 5 is a transverse section on line 5—5 of Fig. 2.

In the accompanying drawing I have not attempted to show the parts in their relative proportion and thickness of wall material and it will be understood that this will be varied according to the material used but in general the gauge of material shown in the drawing is much thicker than in actual practice where metal is employed.

In the embodiment of my invention illustrated, the casing 1 is of cylindrical cross section provided with an integral top 2 and a detachable bottom 3, the bottom being threaded to the side wall casing for convenience in assembling the parts. A gasket 4 is employed to provide an airtight joint. The casing has a longitudinally elongated side wall opening 5 and a central top opening 6. The bottom portion of the casing—

that is, the portion of the casing below the opening 5 constitutes a pump cylinder 7.

The cylindrical plunger 8 is hollow to provide a liquid receptacle chamber 9, the plunger being preferably provided with a suitable cup packing 10 at its lower end.

The air tube 11 is disposed centrally, opening through the head 12 of the plunger to the cylinder 7 so that air compressed within the cylinder is forced through the air tube to the discharge port 13 of the air tube. The air tube projects through the opening 6 in the top of the casing and is closed at its upper end, its upper end constituting a finger piece 14 for manipulating the plunger, the spring 15 within the cylinder acting 16 to return the plunger to its initial position.

The liquid or eduction tube 16 depends into the liquid chamber and is open at its lower end as shown at 17 for the entrance of liquid thereto. At its upper end, the eduction tube is provided 20 with a tapered nozzle 18 having a restricted delivery orifice or passage 19, this restricted delivery orifice being relatively short and of substantially less diameter than the internal diameter of the eduction tube. The eduction tube 25 is provided with a vent opening 20 opening to the liquid chamber above the normal liquid level thereof.

It will be noted that the nozzle 18 is disposed in alignment with the air discharge port 13 so 30 that the air is discharged across the nozzle thus creating an aspirating effect or action, pulling up the liquid from the liquid chamber and atomizing it. The nozzle is arranged in alignment with the opening 5 when finger piece 14 is depressed 35 so that the atomized liquid is discharged through the opening.

In the upper end of the casing I seat an annular gasket-like closure member 21 of rubber or other resilient material against which the nozzle 40 impinges when the plunger is in its elevated or initial position. In this embodiment illustrated, the port 13 is also covered by the closure member when the parts are in initial position as shown in Fig. 3. This member 21 is retained in position 45 by means of indentations 22 in the wall of the casing below the closure member and these indentations also serve as stops limiting the upward movement of the plunger and consequently the extent of embedding the nozzle in the resilient closure.

The liquid chamber is provided with a filler neck 23 which projects through the opening 5 in the casing and is provided with a threaded closure 24. This filler neck is of very considerable ad- 55

vantage in that it makes it possible to fill the liquid chamber from a bottle with little danger of spilling the liquid or of the liquid being impeded in its entrance to the chamber by the escaping air. In the embodiment illustrated, the filler neck 23 is notched at 25 to receive the eduction tube and thus constitutes a supporting element for the eduction tube.

With the arrangement of parts in accordance with my invention, they may be very economically produced and assembled; at the same time are not likely to get out of repair. By forming the eduction tube as I have described with the short restricted nozzle orifice and the vent 20, there is an inrush of air at each stroke to compensate for the liquid ejected and this serves to prevent the nozzle orifice from becoming clogged as is likely to be the case where long passages of small diameter such as is required in the nozzle are provided. It will be observed that little material of any obstruction is required in order to carry it into the large bore of the eduction tube and when it is considered that the parts are shown very substantially enlarged so far as thickness of material is concerned, the point will be more readily understood. The vent 20 increases this action and also minimizes any tendency of the liquid to escape by capillarity. Furthermore, vent 20 enables the device to be manipulated in either upright or upside down position to produce an effective atomized discharge without undesirable leakage of the liquid from the liquid chamber.

When the device is held in upright position and the finger piece 14 depressed the sub-atmospheric pressure created in eduction tube 16 by the air blast cutting across the point of discharge thereof is greater than can be compensated by the air in the liquid chamber passing through vent 20. Consequently, since the inside of the eduction tube is moist with the liquid, the liquid is drawn up with the air in the tube, aided greatly by the capillary action of the liquids, in a sort of an emulsified state, giving a very fine and desirable break-up or atomization of the liquid at the point of discharge. At the end of the pressure stroke, the air passes back through the eduction tube and out through the vent therein to the liquid chamber to equalize the pressure in the liquid chamber. In doing this, the point of discharge of the eduction tube, i. e. nozzle opening 19, is cleaned by the inrushing air. This is a very desirable feature.

Should the device be operated bottom side up, an entirely different action takes place. Liquid then enters the eduction tube from the liquid chamber 9 through vent 20 and is sprayed out at the discharge nozzle. At the end of the pressure stroke, the air enters the discharge end of the eduction tube and travels the full length of that tube to join the remaining air at the top of the liquid chamber to equalize the pressure therein. In doing so, the liquid is prevented from escaping through the eduction tube at the end of the stroke by the inrushing air. This inrush of air is caused by the partial vacuum produced by the blast of air across the discharge end of the eduction tube drawing out the contents of the liquid chamber. When this blast is discontinued, the partial vacuum produced draws the air back into the chamber.

My device is exceedingly simple and compact in nature. The gasket member 21 insures closure of the nozzle and opening 13 when the device is in inoperative position and there are no relatively sliding parts through which leakage of fluid can

occur. The closure members 21 are very economical and can be quickly seated and secured in position as by indenting at 22 and the indentations do constitute a stop means for the plunger.

I have illustrated and described my improvements in a very practical embodiment thereof. I have not attempted to illustrate certain modifications and adaptations which I contemplate as it is believed that this disclosure will enable those skilled in the art to embody or adapt my improvements as may be desired.

Having thus described my invention, what I claim as new and desire to secure by Letters Patent, is:

1. In an atomizer, the combination of a cylindrical casing having a longitudinally elongated side opening adjacent its top, and a central opening in its top, the bottom portion of the casing constituting a pump cylinder, a cylindrical plunger slidable in said casing and provided with a liquid chamber, said plunger being provided with a central air tube open at its lower end to said cylinder and having a portion projecting through the top of said casing to provide a finger piece for actuating the plunger, a spring arranged within said cylinder and acting to urge said plunger upwardly, an eduction tube depending within said liquid chamber and provided with a nozzle at its upper end, said air tube being provided with an air delivery port disposed to discharge across said nozzle, said nozzle being aligned with said opening in said casing so that the atomized liquid is discharged through said opening when the plunger is actuated, and a resilient annular gasket-like closure member arranged in the upper end of said casing and with which the nozzle impinges when the parts are in initial position, the wall of said casing being indented below said closure member for retaining it and to provide stops for said plunger.

2. In an atomizer, the combination of a cylindrical casing having a longitudinally elongated side opening adjacent its top, and a central opening in its top, the bottom portion of the casing constituting a pump cylinder, a cylindrical plunger slidable in said casing and provided with a liquid chamber, said plunger being provided with a central air tube open at its lower end to said cylinder and having a portion projecting through the top of said casing to provide a finger piece for actuating the plunger, a spring arranged within said cylinder and acting to urge said plunger upwardly, and an eduction tube depending within said liquid chamber and provided with a nozzle at its upper end, said air tube being provided with an air delivery port disposed to discharge across said nozzle, said nozzle being aligned with said opening in said casing so that the atomized liquid is discharged through said opening when the plunger is actuated.

3. In an atomizer, the combination of a cylindrical casing having a longitudinally elongated side opening adjacent its top, and a central opening in its top, the bottom portion of the casing constituting a pump cylinder, a cylindrical plunger slidable in said casing and provided with a liquid chamber, said plunger being provided with a central air tube open at its lower end to said cylinder and having a portion projecting through the top of said casing to provide a finger piece for actuating the plunger, said liquid chamber being provided with a filler neck projecting substantially through said opening in said casing and provided with a closure cap, a spring arranged within said cylinder and acting to urge

said plunger upwardly, and an eduction tube depending within said liquid chamber and provided with a nozzle at its upper end, said air tube being provided with an air delivery port disposed to discharge across said nozzle, said nozzle being aligned with said opening in said casing so that the atomized liquid is discharged through said opening when the plunger is actuated.

5 4. In an atomizer, the combination of a casing having a side opening and a top opening, the bottom portion of the casing constituting a pump cylinder, a plunger slideable in said casing and provided with a liquid chamber, said plunger being provided with an air tube closed at its upper end 10 and open at its lower end to said cylinder and

having a portion projecting through the opening in the top of said casing to provide a finger piece for actuating the plunger, a spring acting to urge said plunger to its initial position, a liquid eduction tube depending within said liquid chamber and provided with a nozzle, said air tube being provided with an air delivery port disposed to discharge across said nozzle, and a resilient annular nozzle closure member seated in the upper end of said casing to close the nozzle when the parts 15 are in initial position, the wall of the casing having indentations therein below said closure member for retaining it in position and to provide stops for said plunger.
